UNITED STATES PATENT OFFICE.

FREDERICK A. FELDKAMP, OF NEWARK, NEW JERSEY, ASSIGNOR TO ELECTROLYTIC PRODUCTS CO., A CORPORATION OF NEW JERSEY.

METHOD OF ASSEMBLING RADIATOR-SECTIONS.

1,077,058.

Specification of Letters Patent.

Patented Oct. 28, 1913.

Application filed November 5, 1912. Serial No. 729,571.

To all whom it may concern:

Be it known that I, FREDERICK A. FELDKAMP, a citizen of the United States, residing at Newark, in the county of Essex and State of New Jersey, have invented certain new and useful Improvements in Methods of Assembling Radiator-Sections; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to a novel method of assembling a plurality of radiator-sections or cooling units and securing them in their assembled relation by means of the connecting strips of the general character and construction set forth in my previous application for Letters-Patent, filed September 27, 1912, Serial Number 722,663.

The present invention, therefore, has for its principal object to provide a novel method or process of primarily assembling a plurality of thin and hollow radiator-sections over an arrangement of narrow strips, preferably in the form of wire, and formed with U-shaped portions, disposed in a series of grooves or channels therefor and formed in a plate-like body or bodies, then placing the narrow edge-portions of the radiator-sections down upon and within said U-shaped portions of the said strips in the said grooves or channels of said body or bodies, securing the parts in their assembled relations, and finally dipping the perforated and grooved plate, with the said narrow strips and the radiator-sections, in the manner hereinafter stated, in a soldering or tinning solution, in order that at one time all of the U-shaped portions of the connecting strips will be solidly united with the marginal edge-portions of the plurality of radiator-sections or cooling units.

With the various objects of the present invention in view, the invention consists in the novel process or method for connecting or securing the connecting strips or wires to the marginal edge-portions of a plurality of radiator-sections.

The invention is clearly illustrated in the accompanying drawings, in which:

Figure 1 is a plan view of a pair of perforated and grooved or channeled plates with the strips or wires arranged in position in the grooves of the said plates, said view showing in connection with the said plates, 60 diagrammatically, a fluting roll, a pair of guide-bars, and an arrangement of knives for severing the strips or wires after having been arranged in the grooves or channels of the plates. Fig. 2 is an enlarged plan 65 view of one of the said perforated and grooved plates with the narrow strips or wires in place, showing in plan view upon said plate an assembling frame and a number of the radiator-sections held in their 70 assembled relation upon the grooved plate by the said assembling frame. Fig. 3 is a transverse vertical section, taken on line 3-3 in said Fig. 2; and Fig. 4 is a vertical cross-section, taken on line 4-4 in said 75 Fig. 2, looking in the direction of the arrow α . Fig. 5 is a vertical cross-section, taken on line 5-5 in said Fig. 1, said view being made on an enlarged scale, and showing in connection therewith a holding bar 80 for retaining the narrow strips or wires in the grooves or channels of the plate. Fig. 6 is an elevation of the holding bar removed from the plate; and Fig. 7 is an enlarged end view of the same. Fig. 8 is a front 85 elevation of the retaining frame shown in said Figs. 2 and 3, removed from the perforated and grooved or channeled plate. Fig. 9 is a front elevation of the two perforated and grooved or channeled plates 90 with the devices therebetween in their connected and assembled relations, ready for the dipping step of the process.

Similar characters of reference are employed in all of the above described views, 95 to indicate corresponding parts.

In carrying out the several steps of the novel method or process of securing by means of soldering or by the tinning method, the narrow strips or wires to the hollow 100 units of the radiator, the apparatus illustrated in the several figures of the drawings is employed. This apparatus consists, essentially, of two plates 1 and 2, the plate 1 being formed with suitably formed ears or 105 lugs 3, each of which is provided with an upwardly projecting dowel-pin 4. The plate 2 is likewise formed with correspondingly located ears or lugs 5, each ear or lug 5 having a hole or perforation 6, into and 110

through which holes or perforations the screw-threaded end-portions 7 of the dowel-pins 4 are passed, and are adapted to receive suitable nuts 8 for securing the parts in their assembled relations, substantially as illustrated in Fig. 9 of the drawings and for the purposes hereinafter more fully specified. The said ears or lugs 5 of the plate 2 are also provided with dowel-receiving holes or perforations 9.

10 As will be seen from an inspection of Fig. 1 of the drawings, the plate 1 is made with a series of parallel and laterally extending grooves or channels, as 10, the sides 15 of which taper substantially in the manner shown, so that each channel is wider at and across the top than across the bottom, and 11 indicates a series of narrow strip or wire-receiving grooves or channels which extend longitudinally across the upper surface of 20 the plate 1, and cross the said laterally extending grooves or channels 10 in the manner illustrated. At the several crossings of 25 said grooves or channels 10 and 11, the body of the plate 1 is provided with a plurality of holes or openings, as 12, the diameter of each hole or opening 12 preferably being equal to the distance across the widest part of each groove or channel 10, as will 30 be clearly evident from an inspection of Figs. 1, 2, 3 and 4 of the drawings. The grooves or channels 10 are also made much deeper than the grooves or channels 11, for the proper arrangement of the narrow strips 35 or wires 13 and their U-shaped parts 14 in the respective channels or grooves, as will be clearly understood from an inspection of Fig. 3 of the drawings.

40 Referring now once more to Fig. 1 of the drawings, it will be seen that the plate 2 is also made with a series of parallel and laterally extending grooves or channels 15, the sides of which also taper substantially in the manner shown, so that each channel is 45 wider across the top than across the bottom, and 16 indicates a series of narrow strip or wire-receiving grooves or channels which extend longitudinally across the upper surface of the plate 2, and across the 50 said laterally extending grooves or channels 15 in the manner shown. At the several 55 crossings of said grooves or channels 15 and 16, the body of the plate 2 is provided with a plurality of holes or openings 17, the diameter of each hole or opening 17 preferably being equal to the distance across the widest part of each groove or channel 15. The 60 grooves or channels 15 are also made much deeper than the grooves or channels 16, for the proper arrangement of the narrow strips or wires 13 and their U-shaped parts 14 in the respective channels or grooves. The 65 said plate 2 is also provided with a pair of perforated ears or lugs 18, with which are suitably connected, by means of nuts 19, a

pair of rod-like elements or members, as 20, which are bent, as at 21, to provide suitable handles or lifting means for raising and reversing the plate 2 from its position indicated in Fig. 1 of the drawings to that 70 represented in said Fig. 9, and for the purposes of suspending and properly handling the two connected plates 1 and 2 during the dipping steps of the soldering or tinning process.

75 In carrying out the different steps of the process, the two plates 1 and 2 are arranged end to end, preferably as shown in said Fig. 1, with a slight space 22 between said plates, and a suitable cutter or severing means 23, 80 located above said space and adapted to enter the same. At the other end of said plate 1 is suitably located another cutter or severing means 24, a pair of suitably formed and perforated strip or wire-guides, as 25 85 and 26, and a fluting means 27 for providing the strips or wires 13 with the previously-mentioned and properly distanced U-shaped parts 14. The said cutters or severing means 23 and 24, the said guides 25 90 and 26, and the fluting means 27, are merely diagrammatically represented, and these devices may be of any suitable and well-known construction. The various devices and parts having been arranged in this manner, the narrow strips or wires 13 are first 95 drawn through the perforated guide 25, and passed into and through the fluting means 27, where the strips or wires 13 are provided with the equally distanced U-shaped portions 14. The strips or wires 13 are then 100 drawn through the perforated guide 26, and located in the aligned grooves or channels 11 and 16 of the respective plates 1 and 2, with the U-shaped portions 14 of the strips or 105 wires 13 located in and extending downwardly into the deeper grooves or channels 10 and 15 of the respective plates 1 and 2, at the crossing of the said grooves or channels 10 and 15 with the respective grooves 11 and 16, so that the said U-shaped portions 14 of the strips or wires 13 will be 110 variously located in the holes or openings 12 of the plate 1 and the holes or openings 17 in the said plate 2, and will extend diametrically across the said openings, as will be clearly evident from an inspection of the several figures of the drawings. The desired number of narrow strips or wires 13 having thus been arranged in the several 115 grooves or channels of the two plates 1 and 2, the cutters or severing means 23 and 24 are suitably operated, so that the said strips or wires are cut into short lengths, and that each plate 1 and 2 will be independently 120 provided in its grooves or channels with a plurality of such strips or wires 13. That the said strips or wires 13 may be properly held and retained in the various grooves or channels of the plate during the cutting 125 130

or severing step, and also during the following steps of the process, an open metal frame, as 28, is placed over the strips or wires 13 in the grooves or channels in the plate 1, the frame 28 serving also another purpose for properly spacing and retaining the radiator-sections or units 29 vertically in alignment with the respective laterally extending grooves or channels 10 of said plate 1. For the same reason, that the narrow strips or wires 13 are properly held and retained in the various grooves or channels of the plate 2, during the cutting or severing step, and also during the following steps of the process, a pair of holding bars 30 are arranged across the strips or wires 13 and the respective ends of the plate 2, said bars 30 being provided at their end-positions with split pins or dowels 31, which are forced into holding engagement with the holes or perforations 9 of the ears or lugs 5 of the said plate 2, as will be clearly understood from an inspection of Fig. 5 of the drawings. The frame 28 having been placed upon the grooved or channeled surface of the plate 1, the desired number of radiator-sections or units 29, to the marginal edge-portions of which the said narrow strips or wires 13 are to be secured by soldering or by the tinning process, are then inserted in suitably spaced cut-away or grooved portions 32, as shown in Fig. 2 of the drawings, with the marginal edge-portions 33 of the said radiator-sections or units arranged in the laterally extending grooves or channels 10 of the plate 1, and resting directly in the U-shaped portions 14 of the said strips or wires 13, as indicated in Fig. 3 of the drawings. The plate 2, with the series of narrow strips or wires 13 arranged and held in the various grooves or channels of said plate, in the manner hereinabove stated, is now raised by means of the handles or lifting devices 21, and brought into its inverted position over the marginal edge-portions 34 of the radiator-sections or units 29 held by means of the frame 28 upon the plate 1. Upon the lowering of the plate 2, the edge-portions 34 of the said radiator-sections or units 29 enter the laterally extending grooves or channels 15 in said plate 2, said edge-portions resting also directly in the U-shaped portions 14 of the narrow strips or wires 13 which are located in the channels or grooves 16 of the said plate 2, as will be clearly evident from an inspection of Fig. 9. At the same time, the previously-mentioned dowel-pins 4 of the lugs or ears 3 of the plate 1 enter the holes or perforations 6 in the lugs or ears 5 of the plate 2, and by means of the nuts 8 which are screwed upon the projecting ends of the said pins 4, the various devices and parts are securely maintained in their assembled relations, ready for the dipping steps of the process. The bottom of the plate 1 is now dipped or placed for a short time in a bath of fluid solder or liquid tinning material to such depth that the fluid will fill the holes or perforations 12 in the plate 1, and that the U-shaped portions 14 of the strips or wires 13, and the exposed edge-portions of the radiator-sections or units 29 will also become immersed in the liquid solder or tinning fluid. Upon the removal of the plate 1 from the bath, sufficient liquid solder or tinning fluid will adhere to the U-shaped portions 14 and the edge-portions of the radiator-sections or units, which immediately solidifies and causes the said parts to be securely and positively united, as will be clearly understood. The devices and parts, in their assembled positions, indicated in said Fig. 9 of the drawings, are now reversed, and the bottom of the plate 2 is then dipped or placed for a short time in the bath of fluid solder or liquid tinning material, and to such a depth that the fluid will fill the holes or perforations 17 in the plate 2, and that the U-shaped portions 14 of the strips or wires 13, and the exposed edge-portions of the radiator-sections or units 29 will also become immersed in the liquid solder or tinning fluid. Upon the removal of the plate 2 from the bath, sufficient liquid solder or tinning fluid will also adhere to the U-shaped portions 14 and the edge-portions of the radiator-sections or units, which immediately solidifies and causes the said parts to be securely and positively united, as will be evident. Upon removing the nuts 8 from the pins 4, the plate 2 can be taken away, and a complete radiator consisting of a plurality of equally spaced radiator-sections or units, securely connected at their front and rear marginal edge-portions by means of the narrow strips or wires 14, is the result, which is easily removed from the plate 1 and the frame 28.

From the foregoing description of the present invention, it will be seen, that I have provided a novel method for simultaneously securing, by soldering or by the tinning process, a great many strips or wires to the marginal edges of a plurality of radiator-sections or units, thus greatly minimizing the labor in assembling the parts, and materially reducing the cost of manufacture.

I claim:—

1. The process or method herein described of simultaneously securing a plurality of narrow strips or wires to the marginal edge-portions of a plurality of radiator-sections or units which consists in the provision of a pair of grooved or channeled and perforated plates, drawing a plurality of narrow strips or wires into and through the grooves or channels of said plates and across

the perforations of said plates, arranging a plurality of radiator-sections or units between said plates with opposite marginal edge-portions of said radiator-sections or units arranged in said grooves or channels and across the perforations and the said narrow strips or wires, and passing liquid solder or tinning fluid into the perforations of said plates, and upon the exposed portions of the said strips or wires and edge-portions of the radiator-sections or units.

2. The process or method herein described of simultaneously securing a plurality of narrow strips or wires to the marginal edge-portions of a plurality of radiator-sections or units which consists in the provision of a pair of grooved or channeled and perforated plates, drawing a plurality of narrow strips or wires into and through the grooves or channels of said plates and across the perforations of said plates, arranging a plurality of radiator-sections or units between said plates with opposite marginal edge-portions of said radiator-sections or units arranged in said grooves or channels and across the perforations and the said narrow strips or wires, passing liquid solder or tinning fluid into the perforations of one of said plates and upon the exposed portions of the strips or wires and edge-portions of the radiator-sections or units connected with said plate, and then passing liquid solder or tinning fluid into the perforations of the other of said plates and upon the exposed portions of the strips or wires and edge-portions of the radiator-sections or units connected with said last-mentioned plate.

3. The process or method herein described of simultaneously securing a plurality of narrow strips or wires provided with U-shaped portions to the marginal edge-portions of a plurality of radiator-sections or units which consists in the provision of a pair of plates provided with laterally extending and longitudinally extending grooves or channels and formed with perforations at the crossings of said grooves or channels, and the laterally extending grooves or channels having greater depth than the longitudinally extending grooves or channels, drawing a plurality of such narrow strips or wires into and through said longitudinally extending grooves or channels and across the said perforations of said plates, arranging a plurality of radiator-sections or units between said plates with opposite marginal edge-portions of said radiator-sections or units arranged in said laterally extending channels or grooves and across said U-shaped portions of the said strips or wires and also across the said perforations, and passing liquid solder or tinning fluid into the perforations of said plates and upon the exposed portions of the strips or wires and edge-portions of the radiator-sections or units connected with said plates.

tions of the said strips or wires and edge- 65 portions of the radiator-sections or units.

4. The process or method herein described of simultaneously securing a plurality of narrow strips or wires provided with U-shaped portions to the marginal edge-portions of a plurality of radiator-sections or units which consists in the provision of a pair of plates provided with laterally extending and longitudinally extending 70 grooves or channels and formed with perforations at the crossings of said grooves or channels, and the laterally extending grooves or channels having greater depth than the longitudinally extending grooves or channels, drawing a plurality of such 80 narrow strips or wires into and through said longitudinally extending grooves or channels and lodging the U-shaped portions of said strips or wires in the deeper laterally extending grooves or channels and across 85 the said perforations of said plates, arranging a plurality of radiator-sections or units between said plates with opposite marginal edge-portions of said radiator-sections or units arranged in said laterally extending 90 channels or grooves and across said U-shaped portions of the said strips or wires, and also across the said perforations, passing liquid solder or tinning fluid into the perforations of one of said plates and upon the exposed 95 portions of the strips or wires and edge-portions of the radiator-sections or units connected with said plate, and then passing liquid solder or tinning fluid into the perforations of the other of said plates and 100 upon the exposed portions of the strips or wires and edge-portions of the radiator-sections or units connected with said last-mentioned plate.

5. The process or method herein described of simultaneously securing a plurality of narrow strips or wires provided with U-shaped portions to the marginal edge-portions of a plurality of radiator-sections or units which consists in the provision of a pair of plates provided with laterally extending and longitudinally extending 105 grooves or channels and formed with perforations at the crossings of said grooves or channels, and the laterally extending grooves or channels having greater depth than the longitudinally extending grooves or channels, drawing a plurality of such narrow strips or wires into and through said longitudinally extending grooves or 110 channels and across the said perforations of said plates, arranging a plurality of radiator-sections or units between said plates with opposite marginal edge-portions of said radiator-sections or units arranged in said laterally extending 115 channels or grooves and across said U-shaped portions of the said strips or wires and also across the said perforations, passing liquid solder or tinning fluid into the perforations of one of said plates and upon the exposed 120 portions of the strips or wires and edge-portions of the radiator-sections or units connected with said plate, and then passing liquid solder or tinning fluid into the perforations of the other of said plates and 125 upon the exposed portions of the strips or wires and edge-portions of the radiator-sections or units connected with said last-mentioned plate.

the said perforations, then dipping first the one plate into a bath of liquid solder or tinning fluid and causing the fluid to flow into the perforations in said plate and around 5 the exposed portions of the strips or wires and marginal edge-portions of said radiator-sections or units, removing the same from said bath and allowing the adhering liquid solder or tinning fluid to solidify, then dipping 10 the other plate in the bath of liquid solder or tinning fluid and causing the fluid to flow into the perforations in said last-mentioned plate and around the exposed

portions of the strips or wires and marginal edge-portions of said radiator-sections or 15 units, and removing the same from the bath and allowing the adhering liquid solder or tinning fluid to solidify, substantially as set forth.

In testimony, that I claim the invention 20 set forth above I have hereunto set my hand this 28th day of October 1912.

FREDERICK A. FELDKAMP.
